UNITED STATES PATENT OFFICE.

ROBERT P. BROWN, OF PHILADELPHIA, PENNSYLVANIA.

DESIGN FOR A PAPER BOX.

SPECIFICATION forming part of Design No. 29,852, dated December 20, 1898.

Application filed January 29, 1895. Serial No. 536,606. Term of patent 14 years.

To all whom it may concern:

Be it known that I, ROBERT P. BROWN, a citizen of the United States, residing in the city and county of Philadelphia, State of Pennsylvania, have invented and produced a new and original Design for Paper Boxes, of which the following is a description, reference being had to the accompanying drawing, which shows a perspective view of a paper box having the form and ornamentation which conjointly constitute my design.

A indicates the paper box, having two straight sides $a a$ and a side a' , curved, substantially as shown, so as to make a sector-

shaped box with the sides $a a$. This side a' , 15 facing the angle formed by the sides $a a$, is ornamented with an inwardly-projecting fringe; (indicated at B.)

The essential feature of my invention is the sector-shaped box having an ornamental 20 fringe on the side a' .

What I claim is—

The design for a paper box substantially as described and shown.

ROBERT P. BROWN.
